CLAIM

The ornamental design for a portable radio, as shown and described.

DESCRIPTION

FIG. 1 is a top, front and left side perspective view of a portable radio showing my new design;

FIG. 2 is a front elevational view thereof;
FIG. 3 is a right side elevational view thereof;
FIG. 4 is a rear elevational view thereof;
FIG. 5 is a left side elevational view thereof;
FIG. 6 is a top plan view thereof; and,
FIG. 7 is a bottom plan view thereof.

The broken-line showings in the drawings are for illustrative purposes only and form no part of the claimed design. The bottom of the radio is unornamented.

FIG. 1

FIG. 2**FIG. 3***FIG. 4**FIG. 5****FIG. 6******FIG. 7***
